(57) **CLAIM**

The ornamental design for a rear bumper for automobiles, as shown and described.

DESCRIPTION

FIG. 1 is an elevational view of a rear bumper for automobiles showing my new design;

FIG. 2 is a top plan view thereof;

FIG. 3 is a side elevational view thereof, the opposite side elevational view being a mirror image; and,

FIG. 4 is a perspective view thereof.

The broken line showings form no part of the claimed design.
